AIR DISTRIBUTING DEVICE

Franz J. Kurth, New York, N. Y., assignor to
 Anemostat Corporation of America, a corpora-
 tion of Delaware

Application March 20, 1939, Serial No. 262,971

6 Claims. (Cl. 98—38)

This invention relates to ventilating apparatus, and has particular reference to improvements in devices for effecting diffused delivery of air from air supply ducts into rooms and other enclosures.

More particularly, the invention relates to air-delivery, air-diffusing devices of the type comprising a series of successively smaller open-ended, hollow, flaring members, spaced successively inwardly of one another to provide therebetween a series of flaring passageways. In a device of this type some or all of the flaring members serve to deflect the supplied air laterally outward and to divide it into a plurality of separate streams which flow, respectively, forwardly through some or all of the separate passageways at reduced velocities as compared with the duct velocity of the air. Because the supplied air has a natural tendency to flow directly forwardly through a device of the type mentioned, and because it is deflected laterally outward by the flaring members, there is produced in the inner side portion of each passageway through which a forward flow of air takes place, a zone of high pressure as compared with the pressure in the outer side portion of each such passageway. As a consequence, instead of there being a forward flow of air throughout the area of each such passageway, there occurs a rearward or aspirating flow of air in the outer side portion of each such passageway. Of course, the rearwardly flowing or aspirated air merges with and is carried forwardly by the forwardly flowing air, with the result that there occurs, within the passageways and in advance of the same, a more or less pronounced intermixing of the supplied air with the air of the room or other enclosure into which the supplied air is delivered. This is of decided advantage in eliminating sensation of draft in cases where there is a temperature differential between the supplied air and the room or other enclosure air, as the supplied air is tempered by the room or enclosure air as it is delivered rather than after delivery. Thus, because of the mixing of the supplied air with the room or enclosure air, and because of the reduced velocity, diffused flow of air caused by the flaring members, any sensation of draft to occupants of a room into which air is supplied through a device of the type mentioned, is practically avoided even in cases of a decided temperature differential between the supplied air and the room or enclosure air and even though relatively small air supply ducts and relatively high duct velocities advantageously are employed.

Devices of the type mentioned as heretofore

constructed usually have comprised a minimum of five flaring members and four flaring passageways in order to obtain required diffusion and reduced velocity of the supplied air. The number of flaring members included in a device of any given neck size is, of course, a measure of the cost of the device, the cost naturally varying with variation in the number of flaring members used. Therefore, it obviously is desirable to construct devices of the type mentioned with the fewest number of flaring members practicable commensurate with the obtaining of desired results respecting diffusion, mixing and reduced velocity of the air. When, however, attempts were made to reduce the number of flaring members below the minimum stated, using flaring members the walls of which were straight from end to end in accordance with common prior practice, it was found that the velocities of the air streams in the passageways were too high and that there was insufficient diffusion and mixing of the air to render the device practical. Thus, there arose the problem of providing a device of the type mentioned having fewer than the minimum number of flaring members stated and which yet would function with efficiency comparable to a device having the stated minimum, or more than the stated minimum, of flaring members.

Accordingly, the general object of the present invention is to provide a device of the type mentioned embodying a construction to solve the problem mentioned; that is, to provide a device which has lesser than the stated minimum number of flaring members, whereby it is more economical to produce than prior devices, and which, at the same time, is practically as effective as prior devices in eliminating any sensation of draft.

With the foregoing general object in view, the invention consists in a device of the type mentioned embodying the novel combination and arrangement of features as will be hereinafter more fully described, illustrated in the accompanying drawing and defined in the appended claims.

In the accompanying drawing:

Figure 1 is a central, longitudinal section through a device constructed in accordance with one practical embodiment of the invention; and

Figure 2 is a fragmentary view looking toward the inlet end of the device shown in Fig. 1.

Referring to the drawing in detail, it will be observed that the present device comprises a larger, outermost, open-ended, hollow, flaring member 10, a second, smaller, open-ended, hollow, flaring member 11 spaced inwardly with respect

to said member 10, a third, still smaller, open-ended, hollow, flaring member 12 spaced inwardly with respect to said second member 11, and an innermost flaring member 13 spaced inwardly with respect to said third member 12. Thus, said members cooperate to provide therebetween three successively smaller, successively inwardly disposed, flaring passageways designated as *a*, *b* and *c*, respectively.

From the smaller or rear, open end of the member 10 a neck 14 extends rearwardly for connection with an air supply duct, thereby to provide for flow of supplied air to the device, while, in accordance with known practice, the smaller or rear, open end of the member 11 is spaced inwardly from the rear, open end of the member 10, and the rear, open end of the member 12 is spaced inwardly from the rear, open end of the member 11, whereby the supplied air is divided into separate streams which flow, respectively, through the passageways *a*, *b* and *c* at reduced velocities as compared with the duct or neck velocity of the supplied air, due to the flaring form of said passageways.

The innermost member 13 may be hollow and of conical form as shown, or it may be of any other suitable flaring shape and may be solid. If it is hollow, it may be either closed or open at its rear end as desired. Moreover, the members 10, 11, 12 and 13 may be connected together in assembled relationship in any preferred manner as, for example, by means of struts 15 in accordance with known practice.

In accordance with the invention the rear end portions 16 of the members 11 and 12 and, if desired, the rear end portion 16' of the member 10, have lesser amounts of flare than the portions of said members forwardly of their said rear end portions. The rear end portion 16' of the member 10 determines the outer limit of the air stream flowing through the passageway *a* and the rear end portions 16 of the members 11 and 12 determine the outer limits of the air streams flowing through the passageways *b* and *c*, respectively. Thus, within the forward end portions of the passageways *b* and *c*, the outer limits of the air streams flowing therethrough are spaced inwardly from the members 11 and 12 defining the outer portions of said passageways, as indicated by the light, dash and dot lines 17. Similarly, if the rear end portion 16' of the member 10 has a lesser amount of flare than the forward portion of said member, the outer limit of the air stream flowing through the passageway *a* will be spaced inwardly from the forward end portion of said member 10.

Air flowing to the device through the neck 14 tends to preserve a direction of motion directly forwardly through the device; i. e., a direction of motion axially with respect to the device. It follows, therefore, that in being divided into separate streams and in being deflected outwardly by the flaring members 11, 12 and 13, the air tends to hug the sides of said members defining the inner sides of the passageways *a*, *b* and *c*, so that, naturally, high air pressures exist at the inner sides of said passageways and comparatively low pressures exist at the outer sides of said passageways. This obviously results in aspiration or drawing of room or enclosure air into the outer side portions of the passageways as indicated by the arrows 18. The aspirated or inwardly drawn air is, of course, picked up by the forwardly flowing air and eventually is de-

livered from the device, but in being picked up and delivered it obviously becomes intermixed with the supplied air. Thus, even in the case of more or less pronounced temperature differentials between the supplied air and the room or enclosure air, little or no sensation of draft due to the temperature differential will be perceptible even at only short distances in advance of the device if provision is made for a sufficient amount of aspiratory action in the respective passageways.

Because the forward portions of the members 11 and 12 have greater amounts of flare than the rear end portions 16 of said members, a much greater aspiratory action in the passageways *b* and *c* is obtained than would be obtained if the rear and forward portions of said members 11 and 12 had equal amounts of flare. Similarly, if the forward end portion of the member 10 should have a greater amount of flare than the rear end portion 16' of said member, a much greater aspiratory action would be obtained in the passageway *a* than in case the forward and rear end portions of said member 10 had equal amounts of flare. In this connection it is pointed out that the forward and the rear end portions of the members 10, 11 and 12 may have any desired amounts of difference in flare to obtain any desired amount of aspiratory action, within practicable limits, in each of the passageways *a*, *b* and *c*. In the present instance there is little difference in flare between the forward and the rear end portions of the member 10; a considerable difference in flare between the forward and the rear end portions of the member 11, and also a considerable difference in flare between the forward and the rear end portions of the member 12, though not so great as between the forward and the rear end portions of the member 11. This is because a considerably lesser amount of air flows through the passageway *c* than through the passageway *b*, due to the considerably smaller area of the rear, open end of the member 12 as compared with the area of the mouth of the passageway *b*. In other words, since more air flows through the passageway *b* than through the passageway *c*, there is provided a greater difference in flare between the forward and the rear end portions of the member 11 than between the forward and the rear end portions of the member 12 to cause a greater aspiratory action in the passageway *b* than in the passageway *c*. By providing a proper relationship between the difference in flare of the forward and the rear end portions of the members 11 and 12, the streams of air flowing from the passageways *b* and *c* may be caused to have substantially the same diffusion and draft-sensation avoiding characteristics.

Because the air flowing from the passageway *a* is directed mainly laterally outward, it is not necessary to have as great an aspiratory action in the passageway *a* as in the passageways *b* and *c*. However, since the outermost passageway *a* of the present device has a more forward inclination than the corresponding passageway of a similar prior device having a greater number of flaring members than the present device, and since, therefore, more air flows through the passageway *a* of the present device at a greater velocity than through the corresponding passageway of a known device, it is important to provide for obtaining a greater aspiratory action in the passageway *a* than in the corresponding pas-

sageway of a similar prior device. This may be done by providing the forward end portion of the member 10 with a greater amount of flare than the rear end portion of said member. It may further be accomplished by imparting a convex curvature or bulged form to the forward end portion of said member 10, thereby to increase the outer, low pressure area of the passageway *a* as compared with the low pressure area which would be provided if the wall of the forward portion of the member 10 were straight from end to end. In fact, it is desirable to impart a convex curvature or bulged form to the forward end portions of each of the members 10, 11 and 12, as thereby, for any given difference in flare between the forward and the rear end portions of said members, greater low pressure areas are obtained in the passageways *a*, *b* and *c* than would be obtained if the walls of the forward end portions of said members were longitudinally straight. Moreover, by convexly curving or bulging the forward end portions of the members 10, 11 and 12, the same results are obtained as would be obtained by increasing the flare of said portions if they were longitudinally straight. Accordingly, because of convexly curving or bulging the forward end portions of the members 10, 11 and 12, desired amounts of aspiratory action may be obtained without excessively flaring said forward end portions.

Preferably, but not necessarily, the forward end portions of the members 11 and 12 have their extreme forward ends extended laterally outward as indicated at 19. The outwardly directed extreme forward end portion of the member 11 thus serves to direct air flowing from the passageway *a* away from the low pressure or aspiratory area of the passageway *b*, and the outwardly directed extreme forward end portion of the member 12 thus serves to direct air flowing from the passageway *b* away from the low pressure or aspirating area of the passageway *c*. In this way, interference of the streams of air flowing from the passageways *a* and *b* with aspiration in the passageways *b* and *c*, respectively, is practically avoided with the result that the aspirating effect in the passageways *b* and *c* is highly efficient.

From the foregoing it is believed to be manifest, assuming equal duct velocities of the supplied air, that, although the air streams flowing through the passageways of the present device have higher velocities than the air streams flowing through the passageways of similar prior devices having greater numbers of flaring members than the present device, the present device is substantially as effective as prior devices in avoiding sensation of draft due to the much greater aspiratory action of the present device as compared with prior devices.

While the novel features of the invention have been illustrated and described in connection with a low-cost device having a lesser number of flaring members than have heretofore usually been provided in similar devices, it is apparent that some or all of said features may advantageously be employed in prior or standard types of such devices having greater numbers of flaring members. It is also apparent that certain features of the invention may be used to the exclusion of other features thereof, either in a device as shown or in a similar device. Furthermore, regarding the lengths of the forward and rear, differently flared portions of the flaring members, it is

pointed out that these may be varied within wide limits, although it is preferred to have the rear end portions 16, 16' only of sufficient lengths to properly control the outer limits of the air streams and to have the forward end portions as long as practicable to afford low pressure areas of maximum length and area.

Without further description it is thought that the features and advantages of the invention will be readily apparent to those skilled in the art, and it will, of course, be understood that changes in the form, proportion and minor details of construction may be resorted to, without departing from the spirit of the invention and scope of the appended claims.

I claim:

1. An air distributing device comprising a plurality of successively smaller, open-ended, hollow, flaring members spaced successively inwardly of one another to provide a plurality of flaring air passageways therebetween, the rear end portion of at least one of said members being straight in cross section and having an amount of flare such that a forward prolongation thereof extends outwardly of the outermost portion of the next adjacent inwardly disposed member by an amount to permit the major portion of air supplied through the passageway between said members to flow in a straight path through said passageway, said first mentioned member, forwardly of its straight-walled rear end portion, being of internal concave, external convex form in cross section and being disposed outwardly of a forward prolongation of the said straight-walled rear end portion thereof to provide in the outer side portion of the passageway between said members a large area for air aspiration.

2. An air distributing device as set forth in claim 1 in which the forward end portion of the first mentioned member is directed outwardly relative to the concavo-convex portion of said member.

3. An air distributing device comprising a plurality of successively smaller, open-ended, hollow flaring members spaced successively inwardly of one another to provide a plurality of flaring passageways therebetween, the forward end portion of at least one of said members being curved outwardly, the rear end portion of said member being straight in cross section and having an amount of flare such that a forward prolongation thereof extends outwardly of the outermost portion of the next adjacent inwardly disposed member by an amount to permit the major portion of air supplied through the passageway between said members to flow in a straight path through said passageway, the portion of said first mentioned member between its straight-walled rear end portion and its front end outwardly curved portion being of internal concave, external convex form in cross section and being disposed outwardly of a forward prolongation of the straight-walled rear end portion of said member.

4. An air distributing device comprising a plurality of successively smaller, open-ended, hollow, flaring members spaced successively inwardly of one another to provide a plurality of flaring passageways therebetween, the rear end portion of each of at least two adjacent of said members being straight in cross section and each having an amount of flare such that a forward prolongation thereof extends outwardly of the outermost portion of the next adjacent inwardly disposed member by an amount to permit the major portion of air supplied through the passageways in

wardly of said members, respectively, to flow in straight paths through said passageways, each of said two members, forwardly of its straight-walled rear end portion, being of internal concave, external convex form in cross section and being disposed outwardly of a forward prolongation of its straight-walled rear end portion, the amount of outward disposition of the concavo-convex forward portion of the outer of said two members with respect to a forward prolongation of its straight-walled rear end portion being greater than the amount of outward disposition of the concavo-convex forward portion of the inner of said two members with respect to a forward prolongation of its straight-walled rear end portion.

5. An air distributing device comprising a plurality of successively smaller, open-ended-hollow,

flaring members spaced successively inwardly of one another to provide a plurality of flaring passageways therebetween, at least one of said members being of internal concave, external convex form in cross section throughout a major portion of its length and being spaced outwardly from the next adjacent inwardly disposed member by an amount to permit the major portion of air supplied through the passageway between 10 said members to flow therethrough in a straight path, thus to insure a large area for air aspiration in the outer side portion of said passageway.

6. An air distributing device as set forth in claim 5 in which the forward end portion of the flaring member particularly defined is directed outwardly relative to the concavo-convex portion of said member.
